UNITED STATES PATENT OFFICE.

GEORGE W. LOMBARD, OF WESTMINSTER, MASSACHUSETTS.

WORKING RATTAN.

SPECIFICATION forming part of Letters Patent No. 292,239, dated January 22, 1884.

Application filed November 12, 1883. (No model.)

To all whom it may concern:

Be it known that I, GEORGE W. LOMBARD, a citizen of the United States, residing at Westminster, in the county of Worcester and State 5 of Massachusetts, have invented certain new and useful Improvements in Guiding Mechanism for Rattan-Splitting Machines; and I declare the following to be a description of my said invention, sufficiently full, clear, and exact to enable others skilled in the art to which it appertains to make and use the same, reference being had to the accompanying drawings, which form a part of this specification.

The object of my present invention is to provide a simple, practical, and efficient mechanism for centering and guiding rattan in front of the working tool or cutters in rattan-splitting machinery, which guide mechanism can be conveniently adjusted, easily operated, and 20 economically made and maintained in working condition. These objects I attain by the mechanism illustrated and described, the particular subject-matter claimed being hereinafter definitely specified.

25 In the drawings, Figure 1 is a front view of my improved guiding mechanism, with a portion of the support-bar shown in section. Fig. 2 shows a plan view of the guide mechanism in connection with the splitting-cutter and feed-rolls, and Fig. 3 is a vertical section through one of the guide devices.

In referring to parts, A designates a support-bar, which rests upon two screw-threaded studs, B, fitted in the bed or table T, to which the 35 bar is retained by bolts C, which pass through slots a in the bar and screw into the bed T, as indicated.

D D indicate grooved rolls or devices for guiding the rattan to the splitting cutter or 40 tool S. Said rolls are mounted on studs d, fixed in the top of swinging arms or guide-blocks E, that are pivoted by studs f to the bar A, upon the top surface of which said swinging blocks have bearing. The pivots f are located sufficiently far in advance of the rolls D to permit 45 of said rolls swinging apart, to allow for irregularities of the material passing between them. The two blocks E are provided with gear-teeth e, which mesh together in the manner illustrated, so that any swinging action of the parts 50 or opening and closing of the guides will be

uniform at both sides of the central line, thus accurately centering the rattan and directing it into the axis of the splitting-cutter S, which latter is located in rear of the rolls D and supported on the bed or frame in the ordinary manner. A flat metal spring, H, of C form or horseshoe shape, is arranged around the pivoted ends of the blocks E, with its ends h h pressing inward the rear ends of said blocks 60 E at a position below the guide-rolls D, the reaction being from one guide against the other through the spring H. Screws I are arranged through the ends of the spring H, the points of which enter depressions in the outer surfaces 65 of the backs. Said screws I serve to retain the spring in proper relation with the parts, and also for regulating the tension of the spring or pressure exerted by the guides against the material passed between them. Eccentric bushings F are arranged around the studs or pivot-bolts f, within the arms or blocks E, whereby the parts can be adjusted to take up any looseness or backlash between the gear-teeth e, or for regulating the relative alignment of the 75 axes of the guide-arms E with each other. Said eccentrics F are made slightly higher than the thickness of the blocks E, so that the stud f, when screwed down, will clamp the eccentric bushing F firmly in position for holding it stationary, while leaving the arms E free to swing on the surface of the bushing.

For facilitating adjustment of the axial centers, screws m are arranged in the parts E, that may be turned in against the eccentrics F, for 85 retaining them in relation to the arms E while effecting adjustment, and before the studs f are turned down to clamp them in place by end-wise pressure. After the studs f are screwed down, the screw m may be loosened to release 90 the parts.

The location of the feed-rolls for forcing the rattan through the machine in relation to the guide devices and cutter S is shown by the circles K. Said feed-rolls may be constructed 95 and operated in any suitable well-known manner, as heretofore employed for passing rattan through the stripping-machines, and any desired number of rolls K may be used, the splitting being effected in the ordinary manner. 100

Vertical adjustment of the guide devices is effected by loosening the bolts C and turning

the screw-threaded studs B to elevate or depress the bar A, said studs being provided with neck portions b, that extend up through slots a' in the bar A, with their ends fitted to receive a screw-driver or wrench. The slots a permit lateral adjustment of the bar and guides, as desired.

By constructing the mechanism as shown and described a very simple, durable, and efficient guide and centering apparatus is produced, readily adjustable and convenient for use, and not liable to become deranged or get out of working order.

What I claim as of my invention, and desire to secure by Letters Patent, is—

1. In a rattan-splitting machine, the combination, with rolls which guide the material to the splitting-cutter, of the guide-supporting arms pivoted for swinging action and connected with each other by intermeshing gear-teeth e, formed on arcs of circles coincident with the pivot-centers of said arms, and means for adjusting the relative distance between their axes of motion, substantially as shown and described.

2. The combination, with the swinging arms or blocks geared to each other, and provided with devices for guiding the rattan to the splitting-cutter, of a flat pressure-spring extending around the pivot-heads in C form, with its ends pressing against the outer sides of the blocks, in the manner set forth.

3. The combination, with the swinging blocks or arms, pivoted as at f, and toothed together for simultaneous action, and provided with means for guiding a rattan to the splitting-cutter, of the flat metal spring arranged as shown, and provided with adjusting-screws, the points of which enter depressions on the

exterior of said arms for retaining and regulating the parts, substantially as set forth.

4. The combination, with the swinging arms E, geared together, and carrying devices for guiding the rattan to the splitting-cutter, of the support-bar A, adapted for vertical and lateral adjustment, upon which said arms are pivoted and supported, as hereinbefore set forth.

5. In a machine for splitting rattan, the combination, with the support-bar A, having the guiding devices mounted thereon, of the screw-threaded studs B, fitted to the bed or frame for upholding said bar, and the clamp-bolts C, substantially as shown and described.

6. The combination of the guide-blocks pivoted for swinging action, and connected with each other for uniform operation by intermeshing gear-teeth, and means for adjusting the axis of their swing movement to compensate for wear in the said gear-teeth.

7. In a guiding device for rattan-splitting machines, an eccentric bushing, F, in combination with the pivot-studs f and guide-blocks E, provided with intermeshing gear-teeth e, as and for the purpose set forth.

8. The combination, with the studs f and guide-blocks E, of an eccentric bushing, F, of slightly greater height than the thickness of the block, whereby said bushing is adapted to be clamped in position by said stud while the block is free to swing thereon, as set forth.

Witness my hand this 7th day of November, A. D. 1883.

GEORGE W. LOMBARD.
